UNITED STATES PATENT OFFICE.

JOSEPH ALBERT DE LONGCHAMP, OF MONTREAL, QUEBEC, CANADA.

CLOSURE FOR RECIPIENTS.

Application filed April 21, 1926. Serial No. 103,589.

The present invention relates to improvements in a hermetic closure for recipients such as glasses, cups, and the like, which will hereinafter be fully described and 5 claimed and is illustrated in the accompanying drawings, in which:—

Figure 1 is a side elevation of a recipient provided with a cover and hermetic resilient seal.

10 Figure 2 is a vertical sectional view through Figure 1.

Figure 3 is a side elevation of a recipient provided with a cover of modified form and hermetic resilient seal.

15 Figure 4 is a vertical sectional view through Figure 3.

Figure 5 is a perspective view of the resilient seal.

Like numerals of reference indicate 20 corresponding parts in each figure.

The main object of the present invention is to provide a uniform closure for recipients, which will fit, for instance, all glasses of supposedly the same diameter. It is

25 a well known fact that in drinking glasses, particularly those of the "blown" type, that their opening or mouth will vary in diameter, according to the amount of contraction or expansion when cooling. It is

30 therefore necessary that the cover should be of such a diameter, that it may readily fit all glasses of a same lot. In some instances, more or less space between the flanged cover and the outer walls of the

35 recipient will be provided, which is readily closed by an elastic band. Supposing that the diameter of the glasses were alike, certain types of glasses have oblique walls, in which case, a space is also provided, which

40 will also be closed by the said elastic band.

Another object of the present invention is to allow for the expulsion of the air contained in the container after it has been sealed, and this cannot readily be done, by

45 any other means than that described hereinafter. When the recipient has been filled with food or otherwise, the cover is placed upon the open end of the container and the elastic band is then placed in position.

50 Immediately afterwards, the said elastic band may be slightly lifted from the container, for a few seconds, and the container is turned upside down, to force the air through the space provided between the

55 wall of the recipient and the flange on the cover, outside of said container, and to

establish a partial vacuum therein, after which the elastic band is placed back into position, to provide an air-tight, leak-proof closure.

Referring to the drawings, 1 is a recipient and illustrated in the drawings, as a glass, the walls 2 of which are oblique, and 3 is a cover of preferably slightly larger diameter than that of the recipient having a perpendicular circumferential flange 4 adapted to project downwardly, whereby a space 5 is provided between the upper oblique edge of the recipient 1 and the inner side of the flange 4.

Over the said flange 4 is placed a flat elastic band 6 which projects downwardly in the form of a skirt from said flange and engages the outer wall of the recipient which closes hermetically the space 5 and simultaneously secures the cover to the said recipient. The space 5 provided between the flange 4 and the wall of the recipient permits the band to be lifted out of contact with the container wall when it is desired to expel air from the interior of said container during the preserving operation. The preserving operation having been completed, the elastic band tightly engages the edge of the cover and the container walls 85 to form a hermetic seal for the recipient.

This feature may be improved by providing a bead 7 on the lower edge of the flange 4, in case the walls of the recipient are not at such a pronounced angle, as 90 shown in Figures 3 and 4. This bead has also the advantage of securing the band 6 on the flange and thus preventing the said band from slipping.

The flat elastic band 6 is preferably of 95 relatively smaller diameter than that of the recipient, so that it should be extended when placing it over the cover, in order that a staunch and hermetic seal be provided. The said band is independent from the cover, so that when it is desired to open the container the said band is readily removed from the cover and the said cover may then be used to close the recipient without the use of the said elastic band.

100 What I claim as my invention is:—

1. A closure for recipients, consisting of a cover of slightly larger diameter than the open end of said recipient, said cover having a circumferential depending flange 110 which extends beyond the walls of said recipient at a suitable distance therefrom,

whereby a space is provided therebetween, and a flat elastic band adapted to engage said flange and the walls of said recipient, whereby said elastic band may be readily 5 lifted from the outer walls of said recipient, for the purpose of aiding the escape of air from the interior of the container.

2. A closure for recipients having oblique walls, comprising a cover provided with a 10 circumferential depending flange which extends beyond the walls of said recipient,

whereby a space is provided therebetween, and a flat elastic band adapted to engage said flange and the walls of said recipient, whereby said elastic band may be readily 15 lifted from the outer walls of the said recipient, for the purpose of aiding the escape of air from the interior of the container.

Signed at Montreal, Quebec, Canada, this 15th day of April, 1926.

JOSEPH ALBERT DE LONGCHAMP.
